(No Model.)

J. M. GUILBERT.
NECKTIE PIN.

No. 430,940.

Patented June 24, 1890.

UNITED STATES PATENT OFFICE.

JOHN MURRAY GUILBERT, OF PHILADELPHIA, PENNSYLVANIA, ASSIGNOR
TO WILLIAM H. HART, JR., OF SAME PLACE.

NECKTIE-PIN.

SPECIFICATION forming part of Letters Patent No. 430,940, dated June 24, 1890.

Application filed September 20, 1889. Serial No. 324,512. (No model.)

To all whom it may concern:

Be it known that I, JOHN MURRAY GUILBERT, a citizen of the United States, residing in the city and county of Philadelphia, State 5 of Pennsylvania, have invented a new and useful Improvement in Neck-Wear Pins, which improvement is fully set forth in the following specification and accompanying drawings.

10 My invention consists of a neck-wear pin having near the point thereof a cross-bar which forms an abutment for the fabric of the article of neck-wear and means for seating said cross bar or piece, whereby it is prevented from shifting.

15 Figure 1 represents a face view of a neck-wear pin embodying my invention. Fig. 2 represents a perspective view thereof on an enlarged scale. Figs. 3, 4, 5, and 6 represent 20 perspective views of modifications.

Similar numerals of reference indicate corresponding parts in the several figures.

Referring to the drawings, A designates a neck-wear pin formed of a wire frame of rectangular form, or approximately so, consisting of the pointed pin proper 1, the side piece 2, the bend 3, which joins said parts 1 and 2, the cross-piece 4, which extends laterally from the end of the side piece 2 opposite to the

30 bend 3 and projecting across the pin 1 and the deflection or depression 5 near the point of the pin, said cross-piece being seated in said depression, whereby it is prevented from shifting. It will be seen that the pin portion

1 is passed through the fabric of the head of 35 the article of neck-wear, a form of which is shown in dotted lines, and the bend 3 is secured to said head by stitches or sewing, whereby the pin is secured in position, the point of the pin projecting in such manner 40 that it may engage with the neckband, as usual in such cases, it being seen that when said band is tightened the part of the fabric about which the pin portion 1 has pierced may be compressed against the cross-bar 4 as 45 a stop, thus holding said part and preventing the same from losing its shape, the pin also reliably retaining its position. Owing to the depression 5, the cross-bar 4, which engages with the walls thereof, interlocks with the 50 portion 1 of the pin, and is thus prevented from shifting.

Having thus described my invention, what I claim as new, and desire to secure by Letters Patent, is—

55 A neck-wear pin composed of a frame of substantially rectangular form, having the pin 1 proper with side piece 2 and cross-piece 4 with one free end, said pin 1 being provided with the depression 5 near the point thereof 60 for seating the cross-piece 4 therein and extended beyond the frame, substantially as described.

JOHN MURRAY GUILBERT.
